UNITED STATES PATENT OFFICE.

CHARLES L. WILKINS, OF COLUMBUS, OHIO, ASSIGNOR TO THE OHIO PUMP & BRASS COMPANY, OF COLUMBUS, OHIO.

HYDRAULIC MOTOR.

No. 878,700.

Specification of Letters Patent.

Patented Feb. 11, 1908.

Application filed May 13, 1907. Serial No. 373,356.

To all whom it may concern:

Be it known that I, CHARLES L. WILKINS, of Columbus, in the county of Franklin and State of Ohio, have invented certain new and useful Improvements in Hydraulic Motors; and I do hereby declare the following to be a full, clear, and exact description of the invention, such as will enable others skilled in the art to which it appertains to make and use the same.

My invention relates to improvements in hydraulic motors and more particularly to that type in which a reciprocating piston is employed,—one object of the invention being to simplify and improve motors of this character, and to enable the employment of a comparatively short cylinder and to obtain a maximum length of the piston stroke.

A further object is to provide means whereby the waste of pressure will be effectually avoided.

A further object is to so construct the main inlet ports that they will admit of a gradual increase of pressure into the cylinder and a gradually increasing volume of exhaust from the cylinder, whereby a modulating effect on the action of the driving piston is provided.

A further object is to provide a motor which shall be strong and complete, and in which the positive reciprocating action of the piston will be effectual with no possible chance of the valves centering.

With these objects in view, the invention consists in certain novel features of construction and combinations of parts as hereinafter set forth and pointed out in the claims.

In the accompanying drawings; Figure 1 is a plan view of the motor with the valve casing removed. Fig. 2 is a bottom plan view of the valve casing with the valves shown in dotted lines. Fig. 3 is a longitudinal sectional view on the line *a—a* of Fig. 4. Fig. 4 is a transverse section on the line *b—b* of Fig. 3. Fig. 5 is a longitudinal sectional view on the line *c—c* of Figs. 4 and 6, and Fig. 6 is a transverse sectional view on the line *d—d* of Fig. 5.

1 represents the cylinder; 11 the piston therein provided with a piston rod 11¹, and 2 the valve casing.

In constructing the cylinder, I provide a casting having a flat top portion 11^a having certain parts hereinafter described and constituting a seat for the valve casing 2.

Ducts 10 and 10¹ are made in the casting for the passage of the motive fluid, and between these ducts, an exhaust port 13 is provided and communicates with a nipple 14 with which the exhaust pipe of the motor is connected. The said casting is provided at its respective ends with integral collars 11^b, 11^c. The collar 11^b is internally threaded for the reception of the head 11^d of the cylinder and the opposite head 11^e is bolted to the collar 11^c. The body of the cylinder consists of a tube 11^f which is inserted into place before the head 11^e is applied. The portions of the casting with which the tube or cylinder body 11^f makes contact are machined to effect a good fit and the tube is secured with hard solder. The head 11^e is provided with a suitable bearing 11^g for the piston rod 11¹.

The valve casing comprises two cylinders 2¹ and 4 in which are located, respectively, a main valve 3 and an auxiliary valve 5. The main valve 3 is provided with two piston heads 8, 8, and two piston heads 8¹, 8¹, thus dividing the valve cylinder 2¹ into five chambers, 16, 16¹, 7, 7¹ and 12. An inlet port 6 for fluid pressure, is provided on the valve cylinder 2¹ and communicates through ports 6¹ and 6² with the chambers 7 and 7¹ so that these chambers will always contain fluid under pressure.

The main valve cylinder is provided with elongated diagonally disposed ports 9, 9¹ which communicate with the ducts 10 and 10¹ for admitting pressure fluid to the ends of the cylinder. Thus, with the main valve 90 in the position shown in Fig. 3, fluid will enter at 6, pass through port 6¹ into chamber 7, and from said chamber through the diagonal port 9¹ to the duct 10 by which the fluid is conducted to one end of the cylinder. The exhaust from the other end of the cylinder will pass through the duct 10¹, port 9 to chamber 12 formed by the intermediate heads or pistons 8, 8¹ of the main valve, and from said chamber, through ports 13, 13¹ to the exhaust outlet 14.

The auxiliary valve 5 is provided with three heads or pistons 21, 21^a and 21^b which form four chambers within the auxiliary valve cylinder 4, said chambers being indicated on the drawings by the reference characters 26 and 26¹ at respective ends of the cylinder 4 and 20, 20¹ formed between the heads 21 and 21^a and 21 and 21^b. Ports 27 and 27¹ connect the chambers 26, 26¹ at 110

respective ends of the auxiliary valve cylinder 4 with the main cylinder ducts 10 and 10¹. The auxiliary valve cylinder 4 is also provided centrally between its ends with a port 28, which is connected by a duct or passageway 28¹ with the exhaust port 13.

A passageway or duct 15 in the upper portion of the cylinder casting terminates at one end in a port communicating with the main cylinder at a point between the center and the outer end thereof. The passageway or duct is provided with an enlarged portion 15^a in which a check valve 29 is located as most clearly shown in Fig. 4. The passageway 15 is connected by a channel 18 and a passageway 19 with the chamber 20 between the heads 21—21^a of the auxiliary valve. A passage 22 is also arranged to communicate with the chamber 20 and is connected by a channel 23 with a passageway 24 which communicates with the chamber 16 in one end of the main valve cylinder 2¹. A passageway 25 connects the channel 18 with the main valve cylinder 2¹ as shown in Figs. 2 and 3 for a purpose hereinafter explained. In a similar manner, a passageway or duct 15¹ terminates at one end in a port communicating with the main cylinder at a point between its center and inner end thereof. The passageway or duct 15¹ is provided with an enlarged portion 15^b in which a check valve 29¹ is located. The passageway 15¹ is connected by a channel 18¹ and a passageway 19¹ with the chamber 20¹ between the heads 21—21^b of the auxiliary valve. A passageway 22¹ is also arranged to communicate with the chamber 20¹ and is connected by a channel 23¹ and a passageway 24¹ with the chamber 16¹ in one end of the main valve cylinder 2¹. A passageway 25¹ connects the channel 18¹ with the main valve cylinder 2¹.

The operation of the motor is as follows:— The piston 11 in the main cylinder, as shown in Fig. 3, is traveling toward the left or outer end; the main valve 3 is stationary at the left hand end of its cylinder, and motive fluid is passing into the main cylinder 1, through inlet 6, port 6¹ chamber 7, port 9¹ and duct 10. The exhaust from in front of the piston 11 is passing out through duct 10¹, port 9, chamber 12, exhaust ports 13, 13¹ and outlet 14. It will be observed that piston 11 in its travel to the left has passed and uncovered the passageway 15. Pressure will therefore be admitted into the chamber 16 between the head and cap 17 of the main valve cylinder, the fluid reaching said chamber from the passageway 15, through channel 18, passageway 19, chamber 20 (formed between the heads 21—21^a of the auxiliary valve), passageway 22, channel 23 and passageway 24. The admission of pressure into the chamber 16 will cause the main valve 3 to travel to the right (Fig. 3) or inner end of its cylinder. As the main valve 3 moves to the right,

its inner head 8¹ will pass over and close port 9¹. As the pressure which is moving the main valve comes through this port, it is obvious that as soon as this pressure is cut off from behind the main valve, the latter will stop in its outward movement and the action of the motor would cease owing to the pressure to duct 10 and the main cylinder being cut off. In order to avoid such stopping of the main valve, the passageways 25—25¹ communicating with the channels 18, 18¹ and the main valve cylinder 2¹, are provided so that before a head 8¹ has closed port 9¹, head 8 of the main valve has uncovered passageway 25 and admits the pressure from chamber 7¹ into channel 18 to reinforce the pressure in chamber 16 and thus prevent any possibility of the main valve 3 not finishing its complete stroke.

Should an expansive motive fluid such as steam or air be employed, the passageway 25, 25¹ could be omitted, but where liquid pressure is used for motive power, the provision of these two auxiliary passages makes the complete stroke of the main valve positive.

It will be observed that before the main valve 3 has changed its position to the right hand end of its cylinder (reference being had to Fig. 3 of the drawing) the contents of chamber 16¹ at the opposite end of the main valve cylinder 2¹ is in exhaust through passage 24¹, channel 23¹, passage 22¹, chamber 20¹, passage 28, channel 28¹, exhaust ports 13—13¹ and outlet 14,—thus removing resistance to the free-movement of said main valve. When the main valve has finished its stroke to the right or inner end of its cylinder (Fig. 3), pressure will be admitted into the left or outer end of the main cylinder 1 from chamber 7¹ through port 9, duct 10¹,—thus reversing the main piston 11. The admission of pressure into duct 10¹ also admits pressure through passageway 27 into the chamber 26 (see Fig. 5) of the auxiliary valve cylinder. This causes the auxiliary valve 5 to travel to the left or inner end of its cylinder, and pressure in the chamber 26¹ at the opposite end of the auxiliary valve cylinder will exhaust through passageway 27¹, duct 10, ports 13—13¹ and outlet 14. Thus it will be seen that the reversing of the auxiliary valve takes place as soon as the reversing of the main valve admits pressure into the duct 10¹. The reversing of the auxiliary valve 5 to the opposite end of its cylinder, arranges the passageways for the proper distribution of motive fluid under pressure and also the exhaust. For the reversing of the main valve 3, at the proper time, passageways 19¹ and 22¹ are connected by chamber 20¹ formed by heads 21 and 21^b of auxiliary valve 5, and passageway 25¹ is closed by the inner head 8¹ of the main valve. This places chamber 16¹ in direct communication with 130

the passageway 15¹ so that when the piston 11 has passed the port 15¹ in its travel to the inner end of the driving cylinder 1, pressure will be admitted into the chamber 16¹ to reverse the main valve 3. The chamber 16 at the opposite end of the main valve will be in exhaust as passageway 24 is in direct communication with exhaust port 13, through the medium of channel 23, passageway 22, chamber 20, passageway 28, and channel 28¹.

Returning now to the position of the parts shown in Fig. 3, it will be observed that after the main piston 11 has passed the passage 15 on its outer stroke to the left, pressure will be in said passage 15 and its connecting channels, the same as in cylinder 1 to the right of the piston 11 until the main valve has been reversed, when the space on the right of piston 11 will be in exhaust. This will place the passage 15 in exhaust also until piston 11 re-passes going to the right on its reverse stroke, when the pressure that is driving piston 11 to the right again enters the passage 15. During the interval of time that passage 15 is in exhaust, there would be a waste of pressure from chambers 7¹ and 26 through passageways 19 and 25, channel 18 and passage 15 into the exhaust pressure in cylinder 1, if it were not for the presence of the check valve 29 in the passage 15. Valves 3 and 5 have traveled to the opposite ends of their cylinders from their positions shown in the drawings, consequently the inner head 8 of the main valve 3 that has been covering and closing off passage 25, has passed by and uncovered it, allowing pressure from chamber 7¹ to enter channel 18 that leads to top of check valve 29 in passage 15. Head 21^a on the auxiliary valve 5 has passed over passageway 19 to a position between this passageway and passageway 22, thus making the latter the terminal of channel 23 that leads from chamber 16, in connection with passage 28 through the medium of chamber 20 formed by heads 21—21^a of auxiliary valve 5. The position of the auxiliary valve places duct 10¹, passageway 27, chamber 26, passageway 19, channel 18, and passageway 25 all in connection, and all containing pressure. The pressure coming from chamber 7¹ through port 9 and duct 10¹, passageway 27 into chamber 26, through passageway 25 and connecting with passageway 19 by means of channel 18 that terminates in the enlarged portion of passageway 15 which contains the check valve 29. The lower end of passageway 15 is in connection with the exhaust pressure in the right hand end of the cylinder 1 until piston 11 has passed by it on its reverse stroke, when the pressure is also in passageway 15 on the under side of the check valve. At this time, all of the outer end of the motor is under pressure except chamber 16, which is in exhaust (for reversing when

piston 11 passes passageway 15¹) with exhaust port 13, through the medium of passageway 24, channel 23, passageway 22, chamber 20 (formed by heads 21—21^a of auxiliary valve 5), passageway 28 and channel 28¹. The position of the auxiliary valve 5 not only puts chamber 16 in exhaust through passageway 24, channel 23, passageway 22, chamber 20, passageway 28, channel 28¹ and exhaust port 13, but it also places passageway 27 through which pressure is passing from duct 10¹, in connection with passageway 19 and channel 18, into which pressure is entering from passageway 25 from chamber 7¹ of the main valve cylinder,—so that duty of check valve 29 is to prevent the waste of motive pressure during the interval of time that it requires for piston 11 to pass and repass passageway 15 in its travel. This period is of short duration, as it occurs at the end of the stroke.

Various changes might be made in the details of construction of my invention without departing from the spirit thereof or limiting its scope and hence I do not wish to limit myself to the precise details herein set forth.

Having fully described my invention what I claim as new and desire to secure by Letters-Patent, is:—

1. In a motor, the combination with a main cylinder and a piston therein, of two valve cylinders, main and auxiliary valves in said valve cylinders, the main valve cylinder having ports communicating with the ducts of the main cylinder, channels communicating with the main cylinder between the center and ends of the latter and with the auxiliary valve cylinder, these channels having ports or passageways intermediate of their ends communicating with the main valve cylinder to insure the completion of the stroke of the main valve channels communicating at one end with the auxiliary valve cylinder and at their other ends with the respective ends of the main valve cylinder, and exhaust ports communicating with both of said valve cylinders.

2. In a motor, the combination with a main cylinder, and a piston therein, said cylinder provided with ducts leading to respective ends thereof, of two valve cylinders, a main valve in one valve cylinder, an auxiliary valve in the other valve cylinder, said main valve cylinder having ports communicating with the ducts of the main cylinder, channels or passageways communicating at one end with the main cylinder between the center and the respective ends thereof, and at their other ends with the auxiliary valve cylinder, check valves in these channels or passageways, channels or passageways communicating at one end with the auxiliary valve cylinder and at their other ends with the respective ends of the main valve.

cylinder, and exhaust ports communicating with both of said valve cylinders.

3. In a motor, the combination with a main cylinder and a piston therein, said cylinder having ducts communicating with the respective ends thereof, of a main valve cylinder having ports communicating with the ducts of the main cylinder, an auxiliary valve cylinder provided with ports communicating with the ducts of the main cylinder, a main valve, an auxiliary valve, means for conveying the pressure from the main cylinder to the respective ends of the main valve cylinder, said means controlled by the movements of the auxiliary valve, and means for connecting both valve chambers with an exhaust outlet.

4. In a motor, the combination with a main cylinder, a piston therein, of two valve cylinders, a main valve in one of said cylinders, an auxiliary valve in the other valve cylinder, the main valve cylinder having elongated diagonally disposed ports for the passage of fluid to and from the main cylinder.

5. In a motor, the combination with a main cylinder and a piston therein, of two valve cylinders, a main reciprocating valve in one valve cylinder and comprising a series of heads dividing said cylinder into five chambers, an auxiliary reciprocating valve in the other valve cylinder and having a series of heads dividing the auxiliary valve cylinder into four chambers, a channel or passageway communicating with the main cylinder at each side of the center thereof, each of said channels or passageways adapted to communicate with a chamber of the auxiliary valve cylinder, and other channels or passageways adapted to communicate with the same chambers of the auxiliary valve cylinder and connected respectively with the end chambers of the main valve cylinder.

45 6. In a motor, the combination with a main cylinder and a piston therein, of two valve cylinders, a main valve in one valve cylinder having a series of heads dividing said valve cylinder into a series of chambers, an auxiliary valve in the other valve cylinder and having a series of heads dividing said auxiliary valve cylinder into a series of chambers, said main valve cylinder having ports communicating with the main cylinder, means for conducting fluid from the main cylinder to chambers of the auxiliary

valve cylinder, means for conducting said fluid from said chambers of the auxiliary valve cylinder to respective ends of the main valve cylinder, and an exhaust outlet communicating with both of said valve cylinders.

7. In a motor, the combination with a main cylinder and a piston therein, of two valve cylinders, a main valve in one valve cylinder, means providing passageways for fluid from the main cylinder to the ends of the main valve cylinder for shifting the main valve, means for preventing leakage through said passageways, an auxiliary valve in one of the valve cylinders for controlling the flow of fluid through passageways and means for connecting both valve chambers with an exhaust outlet.

8. In motor, the combination of a casting comprising a flattened intermediate portion provided with ducts and ports, and collars beyond the ends of said flattened intermediate portion, a tube secured in said collars and to the under face of said intermediate flattened portion, and heads secured to said collars.

9. In a motor, the combination of a casting having an intermediate portion having ports and ducts and flattened on its upper face for the reception of a valve casing, said casting also comprising hollow extensions at the ends of said intermediate portion and integral collars at the outer ends of said hollow extensions, a tube secured in said casting and constituting the body of a cylinder, and heads for the cylinder secured to the collars at the ends of the casting.

10. In a motor, the combination of a main cylinder, a piston therein, a valve cylinder and a piston therein, the valve cylinder having elongated, diagonally disposed ports for the passage of fluid to and from the main cylinder.

11. In a motor, the combination with a main cylinder and a piston therein, of valve cylinders containing a main and auxiliary valve, the main valve cylinder having elongated, diagonally disposed ports for the passage of fluid to and from the main cylinder.

In testimony whereof, I have signed this specification in the presence of two subscribing witnesses.

CHARLES L. WILKINS.
